UNITED STATES PATENT OFFICE.

I. F. MAYNARD, OF NASHUA, NEW HAMPSHIRE.

IMPROVEMENT IN FLIERS FOR SPINNING MACHINERY.

Specification forming part of Letters Patent No. 33,356, dated September 24, 1861.

To all whom it may concern:

Be it known that I, I. F. MAYNARD, a resident of Nashua, in the county of Hillsborough and State of New Hampshire, have invented and made certain new and useful Improvements in Cotton and Woolen Machinery; and I do hereby declare that the following is a full, clear, and exact description of the same, reference being had to the accompanying drawings, making a part of this specification.

Figures 1 and 3 represent fliers, showing my improvements. Fig. 4 represents a portion of a flier, showing the whirl and pedestal part in a vertical section. Fig. 5 represents an inverted view of the head and nose of my improvements. Fig. 6 represents the nose detached and in a vertical position. Fig. 7 represents a top view of a pedestal and whirl of the ordinary kind. Figs. 8 and 9 represent, respectively, a detachable whirl and a detachable nose formed with left-hand screw-threads and a rounded shoulder connection, as indicated by the curved line of dots.

The nature of my improvements consists in constructing a flier with a left-handed screw attaching whirl and also a left-handed screw attaching nose, each being formed so as to fit onto their respective parts by a rounded shoulder connection or tenon. The employment of the left-handed screw-whirl and nose connection is designed to prevent the loosening of the flier in its rapid rotary motion. The spiral thread of the screw connection runs in an opposite direction to the rotary motion of the flier and whirl. Hence the revolution thereof, in connection with a tension-draft of the yarn against the nose of the flier, combine to keep the parts securely together. Otherwise, were a right-handed screw connection used, the draft or tension of the yarn would invariably loosen the parts.

The better to enable others to be skilled in the construction of my improvements in fliers and to understand more fully the nature, construction, and operation thereof, the following is deemed a sufficient description of the same.

In Fig. 1, *aa* represent an ordinary-shaped whirl, *bb* being the neck part of the whirl, *c²c²* indicating the upper part of the neck. *d* indicates the pedestal part, into which the left-handed screw-thread *e* of the neck fits,

and in the sides of which pedestal the elbows of the arms *ffff* are inserted permanently by screw ends, said arms being made of suitable steel wire. At *gg* is represented the head of the flier, fixed permanently to the upper extremities of the arms. This head *gg* is formed with a female left-hand screw-thread, into which is fitted a correspondingly-formed left-handed male screw-nose *hh*, formed with the conical-shape bore or passage *II*. (Indicated in Fig. 1.)

In Fig. 8 is shown the whirl detached, formed with the left-hand screw-thread, as indicated at *ee*. This whirl is also bored out of the required size for the spindle to fit in, as in the usual manner of employing the flier.

In Fig. 9 is represented the left-hand screw detachable nose of the flier, showing the screw formation *JJ*. This nose, as well as the whirl, is, by means of screw-threads, adjustable in or out, more or less, as may be required, and without tending to work out of its place, as hereinbefore described, whereas a right-hand screw similarly employed will not remain adjusted as desired.

By a reference to Fig. 8 the curved line of dots shows that the upper part of the neck of the whirl is formed with a concave or grooved shoulder *cc*, instead of a flat and sharp edge surface or shoulder-tenon. This formation corresponds with the end formation of the pedestal *b*, (indicated in Fig. 1,) wherein the line of curved dots *c²c²* indicates the convex or rounded tenon-shape connection. The concave groove and convex tenon connection I also apply to the head and nose *gg hh*, Fig. 1.

In the fliers ordinarily used the nose is attached to the head *gg* permanently and rigidly, as shown in Fig. 3 at *hh ii*, and consequently will not admit of adjustability of position nor ready detachability when desired, so as to substitute different sizes of noses. Therefore my improvements present several very important advantages not found pertaining to or resulting from the use of the ordinary kind of fliers, as represented in Fig. 7.

I am aware that fliers have been attached to spindles of cotton machinery by means of a left-hand screw-thread. Therefore such arrangement of fliers I do not claim.

Having described the nature, construction,

application, and operation of my improved fliers and fully represented the several modifications thereof, what I desire to secure by Letters Patent of the United States and claim as of my own invention is as follows, viz:

The construction of fliers with the left-hand screw-whirl attachment *a b c d e* and also the left-hand screw, adjustable and de-

tachable nose *h i j k*, singly or in combination, as set forth and described, and as shown in Figs. 1, 4, 8, and 9.

I. F. MAYNARD. [L. S.]

Witnesses:

Q. A. WOODWARD,
A. W. SAWYER.
